LOOM STOP DEVICE

Cyrus H. Heilig, York, Pa.

Application November 22, 1937, Serial No. 175,941

6 Claims. (Cl. 139—370)

This invention relates to stop devices for looms, by which the operation is interrupted when the wefting shuttle-bobbin has exhausted or nearly exhausted its supply winding of the feeded strand, 5 and has reference more particularly to the weaving of screens or wire cloth.

The primary aim of the same is to provide an improved device of the character stated, which though intended more especially for use on wire-cloth looms will be applicable as well to use on 10 cotton or silk cloth and other fabric looms.

Stop devices of this same general class have been produced heretofore in a number of different forms, applicable to particular objectives or 15 working requirements. Some of these are operable mechanically and others are operable electrically. All have the same special purpose; that is, to stop the loom when a strand nears the end of its feed from a bobbin, as distinguished from 20 those designed to stop the loom when a strand passing therethrough breaks. Most of them have been constructed upon the "follower" principle, wherein a member moving with the decrease of strand winding on the bobbin trips 25 a cam or circuit contact when said winding reaches a certain reduced diameter and thereby causes the loom to be thrown out of action. None of these devices permits the bobbin to exhaust its strand loading down to a minimum remainder 30 and none of them is separable from but actuated by the bobbin itself.

One of the principal objects of the present invention is to provide a device that will be positive acting and permit the exhaustion of bobbin 35 supply to be gauged or carried down to an absolute minimum remainder, or to as low as a twelve or less inch balance winding upon the bobbin, so as to so greatly reduce as virtually to eliminate waste of unused or remnant strand lengths left 40 on the bobbin.

Another of the principal objects is to provide such a device which is separate from but is actuated by the shuttle-bobbin itself and functions in, or as part of, an electrical circuit so as to cause 45 instantaneous stoppage of the loom in a desired movement position as soon as said bobbin has exhausted its supply to the predetermined or gauged remainder point.

Further objects, as well as the general concept 50 and particular advantages of the invention will be revealed and understood best from the following description with reference to the attached drawings, illustrating one practicable embodiment thereof applied in operative relation to a loom.

In said drawings:

Fig. 1 is a plan view of the device in operative position on a loom, showing its mounting and connection with the electrical circuit of which it forms a part;

Fig. 2 is a side elevation of said device as viewed from the right side of Fig. 1, representing its relation to the loom's shuttle-bobbin in the full supply or wind-loaded state of the latter;

Fig. 3 is a similar view of said device broken off in the lower end portion, representing its relation to said bobbin in the nearly exhausted supply load state; and

Fig. 4 is a plan view of a part of the device separated to appear in clearer detail, a portion 15 of the same being revealed in section.

The illustrative device is shown applied to a screen forming loom of the type described in the patent to Mummert, No. 1,643,347, dated September 27, 1927, wherein a shuttle is moved laterally back-and-forth and forwardly at one side in working the weft to place between the warps of the fabric being woven. This shuttle is represented by the member 5, which carries an interchangeable feed bobbin 6 wound with the strand supplying the weft, and one of the transfer-thrust bars passing the shuttle back-and-forth between the warps is shown fragmentarily at 7. The fabric or screen in process of weaving is represented at 8, while the weft strand feeding from the bobbin is denoted by the reference 9. One of the lifting gauge-pins around which the weft is turned together the selvage edge of the weave is shown at 10, along with the spring-arm by which it is actuated.

Said device is mounted upon the frame 11 of the loom in a position opposite and approximating the limit of the shuttle-bobbin's line of forward movement, indicated by the broken curved arrow X in Fig. 1. This mounting is effected 40 in this instance by an adjustable bracket 12, comprising (see Figs. 1 and 2) a base portion 12^a secured as by shown bolting to said frame, a two-part extensible upright portion 12^b set as by the bolts shown, and an upper laterally extended arm 45 portion 12^c providing a horizontal support. Both the base portion 12^a and the upper arm portion 12^c are linearly slotted, substantially as shown, so that capability of adjustment is thus afforded in rectangularly opposite horizontal as well as 50 vertical directions.

Supported on the upper arm portion of this mounting bracket is an oblong duplex plate 13; that is, a plate comprising two substantially corresponding parts 13^a and 13^b superposed one upon 55

the other as a unit (see Fig. 2). This plate is adjustable laterally along said arm of the bracket, to which it is clamped in place by bolts or set-screws 14. Its two parts are also adjustable 5 longitudinally with respect to each other, at right angles to the bracket arm, by the provision of slots 15 as shown in the upper part (see Fig. 1), through which said clamp bolts extend. A micrometric adjustment between them is afforded 10 by an adjustment screw 16 extended through an upturned rearward flange portion 13^{bb} of the lower part against a like portion 13^{aa} of the upper part.

On the upper part of the described duplex 15 plate, a plunger 17 moves within a guide in projection from its forward end. Said guide (see Fig. 4) may consist simply of an elongate longitudinally slotted plate 18 fastened to said part and having forward and rearward guide posts 20 formed respectively by an upturned flange 18^a and a cross-piece 18^b as shown, through which the plunger slides in line with and over its said slotting. The plunger itself in this instance comprises two laminate parts (see Fig. 2), 25 the lower 17^a of which forms its shank and the upper 17^b of which forms a lateral or upwardly extended arm 17'. Of course it may be formed in a single piece or in some other way. Said shank (portion 17^a) is encircled by a spring 19 fitting into the longitudinal slot of the guide- 30 plate, between said arm and the rearward guide post, for holding the plunger normally forward under yieldable tension. The lateral arm 17' carries a button 20, forming an electrical contact 35 means or member, adjustable in a parallel relation toward and from the end of the plunger by an adjustment screw 21, on the end of which it is carried at a spaced distance or different level. This button and its said adjusting screw are 40 insulated from said lateral arm and from the plunger itself by an insulate block 22 and an insulate washer 23 (see Fig. 4) through which the screw extends in contact with a conductor plate 24 clamped to the arm. A connecting post 25 45 connects through the insulate block with said conductor plate.

The lateral arm 17' of the plunger, or the plunger itself, also advantageously carries another arm 26 projecting outward at one side, before which a lever 27 pivoted underneath as at 50 27^a to the mounting bracket or a special fixture therefor and movable within a slot 28 provided in the duplex plate is arranged to be swung backward against said another arm 26 (see Fig. 1), 55 so as to thereby draw and hold the plunger back from its normal full forward projection. A backwardly swung position of said lever and the plunger parts is represented in dotted lines in Fig. 2 and the purpose of this is to permit the 60 plunger to be drawn either entirely out of operative position or only partially out of such position, where it will still operate under delayed action saving wear.

Connected with the aforesaid connecting post 65 25 is one of the wires 29 of an electrical circuit, the other wire 30 of which is ground connected to the shuttle thrust-bar 7 or to some other suitable part of the loom through which current will be communicated to the shuttle-bobbin 6. These 70 wires connect also with a solenoid 31 and a suitable current source represented by the battery 32, thus connecting the device including said shuttle-bobbin in electrical circuit with the solenoid. Said solenoid has its plunger core 33 connected with a tripping lever 34 on the loom, so

as to actuate the latter when its core is energized, and thereby stop the loom in the desired arrest position of the loom's operative movement.

The device is adjusted upon the loom, through its described mounting bracket and duplex plate 5 part, so as to bring the end of the plunger 17 into position to be struck retractively by the loaded shuttle-bobbin 6 in the direct line X of its movement forwardly at one side of the weave area (see Fig. 1) and at a level substantially 10 midway between the heads or side plates 6^a of said bobbin (see Fig. 2). In other words, the plunger is disposed to be struck by the weft strand supply winding 9 on the bobbin, with the top head or side plate of the bobbin at a level to 15 strike the button 20. Said button then is adjusted to a gauged position sufficiently distant from the plunger end to allow the plunger to extend inwardly between the heads toward the barrel or body of the bobbin so as to contact the 20 windings thereon down to the desired limit of remainder; that is, down to the desired depth of winding remaining thereon. This last adjustment, made through the adjusting screws 16 and 21, may be gauged so extremely fine or micro- 25 metrically that the plunger will contact a single layer or a single strand of the winding left on the bobbin and still not contact the barrel or body of the bobbin itself, thereby bringing the limit or minimization of the remainder down to 30 a possible twelve or less inches length. The button is of course held fixed in this gauged or adjusted position, where it is left until there is occasion to readjust it.

Thus the device is adapted, or constructed and 35 arranged, so that each time the shuttle makes its forward movement or stroke, the supply windings on its bobbin 6 strike and retract the plunger 17 carrying with it the button 20. This action may be delayed by setting the plunger partially backward as previously described and as indicated by dotted lines in Fig. 2, which may be desired in some cases, especially after applying a fully loaded bobbin, for the purpose of saving wear. As the windings on the bobbin decrease with continuous feed therefrom, said 40 plunger extends increasingly deeper or further inward toward its barrel and retracts a continually lessening degree or extent. During this procedure the top head or side plate of the bobbin 45 approaches continually closer to the plunger button 20 but does not contact it. Finally, when the windings on the bobbin reach the point of decrease or remainder allowance for which the device has been set, and at which the plunger 50 end contact with said windings no longer prevents, the head or side plate of the bobbin at last strikes or contacts the button 20 and thereby immediately closes the electrical circuit through the same. Thus said button constitutes 55 one closure contact and said shuttle-bobbin, or a part of the same, constitutes the other or opposite contact of the electric circuit. This closing of the circuit by contact of the two members causes the solenoid 31 to be energized and the 60 loom is brought forthwith to a stop in the desired position for which its arrest mechanism has been adjusted.

The advantages of this positive acting stop device will be readily appreciated by those 65 familiar with the weaving art and practice. Its particular value of course resides in the utility of stopping a loom before the shuttle-bobbin, or any bobbin, supply is exhausted. It serves as a mechanical watchman in this respect. Stopping 70

the loom before the bobbin supply has been wholly exhausted, it serves so that an attendant needs only to remove the exhausted or nearly exhausted bobbin and replace it with a new fully loaded one. The likelihood of a strand terminating in the middle of a weave to necessitate a splicing, or any tight or loose (wide) places occurring in the weave from overrun of the machine, is thus substantially eliminated. Moreover, the necessity of picking out a short, loose or tight weave strand and setting it up by hand with resultant irregularities is also substantially eliminated. In other words, the device contributes very substantially to the production of a superior weave of the fabric by eliminating all possible irregularities as the bobbin reaches the end of its supply. A single attendant can keep as many as twelve or more loom machines operating simultaneously when they are equipped with this device. He needs only to move from one machine to another as its operation is interrupted by the device. A continual production on the entire group of machines can thus be maintained and there is no chance of any machine overrunning its bobbin supply. This has been demonstrated in actual practice and the device has proved to be a very material saver of both time and material.

It will be understood that the device may be made and used in different forms to suit different requirements or working conditions, without departing from the spirit and scope or actual concept of the invention. For instance, a different kind or form of mounting bracket might be used, and the plunger might be arranged to operate in a vertical or some other position rather than in the horizontal position shown. Also the device might be mounted to move against the bobbin, rather than to have the bobbin move against it as in the present illustration. Various changes in the form and arrangement of the parts, with different combinations and sub-combinations of its elements may be employed within the general terms and scope of the invention. Therefore, it is not intended that the invention shall be limited by the appended claims to the specific construction illustrated and described.

Having thus described my invention, what I claim as new and desire to secure by Letters Patent of the United States is:

1. A stop device for a loom, comprising, in combination with the operating shuttle of the loom including a bobbin in supply of the weft having the weft applied in windings thereon, a retractile plunger projectingly mounted upon a stationary part of the loom at a point and in a position to be struck endwise by the windings on said bobbin in the operative stroke of the shuttle, means embodying a cooperating pair of slidably related plates associated with the mounting of said plunger for micrometrically adjusting its projection therefrom in the endwise direction of its retractive movement, an electrical contact member carried by said plunger in fixed relation thereto an adjustably gauged distance from its end so as to be struck by a part of said bobbin when the windings thereon have been exhausted down to a predetermined reduction point, and an electric circuit including the striking part of said bobbin as one closing contact thereof and said contact member on the plunger as the opposite closing contact thereof, the said circuit being closed by the bobbin's strike against said member and having means therein actuated upon said closure to bring the loom to a stop.

2. A stop device for a loom, comprising, in combination with the operating shuttle of the loom, an electrically conductive bobbin carried by the shuttle upon which a supply of the weft is expendably applied in load windings thereon, a retractile plunger projectingly mounted upon a stationary part of the loom at a point and in a position to be struck by the windings on said bobbin at the end of each operative stroke of the shuttle, means embodying a pair of plates fitting slidably one upon the other forming part of the mounting of said plunger for micrometrically adjusting its degree of projection therefrom in opposite directions along its line of retractive movement, an electrical contact member carried by said plunger in fixed relation thereto an adjustably gauged distance from its end so as to be struck by a part of said bobbin when the windings thereon have been expanded off to a predetermined remainder limit, and an electric circuit including said bobbin as one closing contact thereof and said contact member on the plunger as the opposing other closing contact thereof, said circuit which is normally open being closed by the strike of the bobbin against said contact member and having means therein actuated upon its closure to bring the loom to a stop.

3. A stop device for a loom, comprising, in combination with the operating shuttle of the loom having a bobbin in supply of the weft expending therefrom by the unreel of windings upon the same, a retractile plunger mounted projectingly upon a stationary part of the loom at a point and in a position to be struck endwise regularly by the windings on said bobbin once in every operative stroke of the shuttle, means associated with the mounting of said plunger for micrometrically adjusting its projection therefrom in the opposite directions of its line of retractive movement, said means including a pair of slidably superposed plates on one of which the plunger is carried and the other of which has a screw action against the former in their slide direction parallel with the plunger axis, an electrical contact member carried by said plunger in fixed relation thereto a gauged distance from its end so as to be struck by the side plate part of said bobbin when and only when the windings thereon have been exhausted down to a predetermined reduction point, the said contact member being insulated from and adjustably gaugeable upon the plunger, and an electric circuit including the bobbin as one closing contact thereof and the contact member on said plunger as the opposing other closing contact thereof, said circuit being normally open but ultimately closed by the bobbin's side plate strike against said contact member and having means therein actuating trip mechanism to stop the loom when the same is so closed.

4. A stop device for a loom, comprising, in combination with the operating shuttle of the loom including an electrically conductive bobbin in supply of the weft expending therefrom by unreel of windings upon the same, a retractile plunger projectingly mounted upon a stationary part of the loom at a point and in a position to be retractively struck normally by the windings on said bobbin at a selected point in the regular operative stroke of the shuttle, means forming a part of the mounting of said plunger for micrometrically adjusting its degree of projection therefrom in opposite directions along its line of retractive movement, said means comprising a

pair of slidably superposed plates on one of which the plunger operates and the other of which carries a screw working longitudinally against the former and both being slotted longitudinally in parallel with the plunger co-registerably with common clamp screws extending through said slottings clamping them in adjustment together, an electrical contact member carried by said plunger in fixed relation thereto at a gauged distance from its end and being adjustably gaugeable with respect to the same so as to be struck alternatively by the side plate or head of the bobbin when the windings thereon have been exhausted down to a predetermined remainder length and themselves no longer strike the plunger itself, and an electric circuit including said bobbin as one closing contact thereof and said contact member on the plunger as the opposing other closing contact thereof, said circuit being closed by the strike of the bobbin against said contact member and having means therein actuated to bring the loom to a stop when the same is so closed.

5. A stop device for a loom according to claim 4, wherein the contact member carried by the retractile plunger is insulated from said plunger which is itself a conductor and is micrometrically adjustable to the fixed position a gauged distance from the plunger end according to the radial dimension of the side plate or head of the bobbin with reference to the latter's barrel.

6. A stop device for a loom, comprising, in combination with the frame and operating shuttle of the loom, the latter including an electrically conductive bobbin in supply of the weft expending therefrom back and forth across the work by unreel of windings upon the barrel of the same, a support mounted on a stationary

part of the frame, a spring-pressed retractile plunger projectingly mounted upon said support at a point and in a position in the path of the shuttle-carried bobbin so as to be retractively struck by the windings on said bobbin once in every operative stroke of the shuttle, means associated with the mounting of said plunger on the support for micrometrically adjusting its projection therefrom in opposite directions in its line of retractive movement, said means comprising a pair of slidably superposed plates arranged parallel with the plunger axis on one of which the plunger is carried and the other of which has a screw action against the former in the direction of their slide movement and both being movable longitudinally in parallel with the plunger, an electrical contact member carried by said plunger in fixed relation thereto at a gauged distance from its end so as to be alternatively struck by the side plate or head part of the bobbin when the windings thereon have been expended off to a predetermined remainder limit and themselves no longer strike the plunger itself, said contact member being insulated from and adjustably gaugeable to the fixed distance upon said plunger according to the depth or diametrical dimension of the bobbin head to its barrel, and an electric circuit including said bobbin as one closing contact thereof and said contact member on the plunger as the opposing other closing contact thereof along with means actuated upon its closure to cause stoppage of the loom, said circuit being normally open but being closed by the bobbin's strike against said contact member thereby actuating the stoppage means.

CYRUS H. HEILIG.
